METHOD OF MAKING A COUNTERSUNK
RIVETED JOINT

Donald F. Leonhart, Youngstown, Ohio, assignor to The
Youngstown Steel Door Company, Cleveland, Ohio
Filed Aug. 31, 1964, Ser. No. 393,313
7 Claims. (Cl. 29—509)

This invention relates to riveting, and more particularly to a novel method for flush riveting sheet metal members.

On many single sheathed plug door applications, it is essential that the door have a smooth inside surface. Any protrusions, such as raised rivet heads or other obstructions, cannot be tolerated. Smooth surfaces are essential to eliminate the possibility and hazard of damage to products used in association with the riveted surfaces. For example, it is necessary to have a smooth working surface when loading and unloading rolls of newsprint. If these rolls were allowed to strike or in some other way come into sharp contact with raised projections such as rivet heads, the newsprint would become damaged, resulting in great waste.

Smooth surfaces obtained by riveting means have been achieved in the past. However, these have been achieved with a number of limitations or special, costly requirements. For instance, smooth, riveted surfaces have been obtained where the metallic sheet members were very thin. In other instances, the use of special alloys was necessary to produce the required, smooth, riveted surface. In other cases, special pre-riveting machining operations such as countersinking were needed. Still in other cases the use of special rivets was required. These prior methods have all been inefficient and expensive because of the need for special machining operations and special alloys or rivets to produce riveting operation yielding acceptable results.

The novelty of this invention is that it provides a method that requires no special machining operations before riveting. Also the new riveting operation does not require specially designed rivets. In addition, no special deformation of the rivet is required before the actual riveting operation to achieve a smooth, flush surface on one side of the riveted assembly. Furthermore, no special alloys are necessary, as this novel riveting method uses standard rivets. Finally, this novel riveting operation requires smaller pressing forces because only one metal sheet is deformed in the riveting process instead of two or more sheets having to be deformed as in previous countersunk riveting operations.

Thus, the object of this invention is to provide a simple, economical method for countersinking rivets in substantially heavy gauge metals.

A further object of this invention is to provide a method for driving and countersinking rivets in one continuous uninterrupted pressing operation, requiring no special alloys.

A further object of this invention is to provide a method for driving and countersinking rivets that are standard, not special items.

A further object of this invention is to provide a method for driving and countersinking rivets in one pressing operation not requiring preparatory pre-machining, pre-forming, or pre-deforming operations before the actual riveting.

Further objects and advantages will become apparent from the following specification and claims and examination of the drawings.

FIG. 1 is a fragmentary view of a single sheathed plug door made of sheets of metal riveted together.

FIG. 2 is a partial cross sectional view on line 2—2

2

of FIG. 1 showing in part the riveted construction of a single sheathed plug door.

FIG. 3 is an exploded view of three fragmentary sheets of metal and the rivet that is to hold them together.

FIG. 4 shows the three sheets of metal and rivet in juxtaposition prior to the riveting operation.

FIG. 5 is a fragmentary sectional view of three metal sheets after the flush riveting operation is completed.

FIG. 6 is an exploded view of two fragmentary sheets of metal and the rivet that is to hold them together.

FIG. 7 shows the two sheets of metal and rivet in juxtaposition prior to the riveting operation.

FIG. 8 is a fragmentary sectional view of the two metal sheets after the flush riveting operation is completed.

Referring to the drawings, and particularly FIG. 3, members 10, 12 and 14 represent three metal sheets to be riveted together. The aperture 16 in member 12 is materially larger than apertures 18 and 20 in members 10 and 14 respectively.

The clearance between the diameters of apertures 18 and 20 and the diameters of rivet shank 22, FIG. 4, is only large enough to allow shank 22 to slide through apertures 18 and 20 freely and without interference. However, aperture 16 is materially larger than apertures 18 and 20 so that when members 10, 12 and 14 are in juxtaposition and apertures 16, 18 and 20 are generally concentric, some metal in members 10 and 14 overlaps aperture 16 in member 12. While aperture 16 is materially larger than apertures 18 and 20, aperture 16 is however, substantially smaller than the diameter of the head 28 of rivet 24. Rivet 24 is a flat head rivet requiring no special machining or shaping.

The apertures 18 and 20 in sheets 10 and 14, respectively, can be formed by punching, drilling or by any conventional, feasible or practical manufacturing means. These apertures have parallel walls and require neither special machining operations nor must they be held to unusually close tolerances.

During a riveting operation, a compressing force is applied against the end 26 of rivet 24, FIG. 4, while the rivet head 28 is held stationary. The entire riveting operation is done in one, continuous, uninterrupted operation.

As an axial force is applied against the rivet end 26, the shank 22 begins to be upset and expands. As the shank expands, its length decreases while its diameter increases slightly and contacts the metal on the inside of aperture 18 in member 10.

As rivet shank 22 continues to be compressed, it continues to expand, and the metal in the shank tends to expand in an outward and upward direction as shown in FIG. 5. The expanding metal in shank 22 forces some of the metal in member 10 that is overlapping aperture 16 to extrude upward into and occupy part of aperture 16.

As the shank 22 extrudes the metal in member 10 and displaces it upward, a void space is formed in member 10 in the vicinity of aperture 18. As the upsetting of the rivet shank 22 continues, the swaged metal of the shank 22 occupies the space it has created in member 10. A portion of the deformed shank also occupies part of aperture 16 in member 12.

When the riveting operation is complete, FIG. 5, the rivet is countersunk, and rivet end 26 is flush with the outer surface of member 10. Shank 22 is deformed, having pushed into aperture 16 a portion of the metal in member 10 that was overlapping aperture 16 and having further occupied the space that was created when that part of member 10 was swaged into aperture 16.

Sheets 10, 12 and 14 are now securely locked together, the rivet end 26 being flush with the outer surface of member 10 which offers a continuous, smooth surface.

Referring now to FIG. 6, members 30 and 32 represent two sheets of metal to be riveted together, having apertures 36 and 34, respectively.

Aperture 36 is only large enough to allow shank 38 of rivet 40, FIG. 7, to slide through it freely and without interference. However, aperture 34 is materially larger than aperture 36 so that when sheets 30 and 32 are in juxtaposition and apertures 34 and 36 are generally concentric, some metal in sheet 30 overlaps aperture 34 in sheet 32. Although aperture 34 is materially larger than aperture 36, it is nevertheless substantially smaller than the diameter of the head 39 of rivet 40. Rivet 40 is a flat head rivet requiring no special machining or shaping.

The apertures 34 and 36 can be formed by punching, drilling or by any conventional, feasible, or practical manufacturing method. These apertures require neither special machining operations nor must they be held to unusually close tolerances.

During a riveting operation, a compressing force is applied against the end 42 of rivet 40 while the rivet head 39 is held stationary. The entire riveting operation is done in one, single, continuous, uninterrupted process.

As force is applied against rivet end 42, the shank 38 begins to compress and expand. As the shank expands, its length decreases while its diameter increases slightly and first makes contact with the metal on the inside of aperture 36 in sheet 30.

As rivet shank 38 continues to be compressed, it continues to expand, and the metal in the shank tends to flow in an upward direction as shown in FIG. 8. The expanding metal in shank 38 forces some of the metal in sheet 30 that is overlapping aperture 34 to extrude upward into and occupy part of the space of aperture 34.

As the shank 38 extrudes the metal in member 30 and displaces it upward, a substantially conical space is formed in member 30. As the upsetting of rivet shank 38 continues, the flowing metal of the shank 38 occupies the space it has created in sheet 30. A portion of the deformed shank also occupies a portion of aperture 34 in sheet 32.

When the riveting operation is completed, FIG. 8, the rivet is countersunk and rivet end 42 is flush with the outer surface of sheet 30. Shank 38 is deformed, having pushed into aperture 34 that portion of metal in sheet 30 that was overlapping aperture 34 and having further occupied the space that was created when a part of sheet 30 was extruded into aperture 34. Sheets 30 and 32 are now securely locked together, the rivet end 42 being perfectly smooth and flush with the upper surface of sheet 30.

For ease of description, the principles of the invention have been set forth in connection with several illustrated embodiments showing a countersunk riveting operation. It is not the applicant's intention that the illustrated embodiments nor the terminology employed in describing them be limiting inasmuch as variations in these may be made without departing from the spirit of the invention. Rather, applicant desires to be restricted only by the scope of the appended claims.

The invention claimed is:

1. A method of riveting a plurality of metal sheets having large and small apertures therein which consists of inserting through said apertures a rivet having a head, a shank, and an end portion with the head being adjacent to one side of the sheets and the shank extending through the sheets, the sheet with the larger aperture therein be-

ing between the outer sheet and the head of the rivet, holding said rivet head axially immobile and applying sufficient axial force against the end of the rivet shank to upset said rivet shank, compressing said shank so it expands and deforms the metal sheet nearest the rivet end, and displaces a portion of said sheet into the larger rivet aperture of the adjacent metal sheet, the rivet shank being further compressed and shortened, and assuming a substantially bulbous shape and occupying the space created by the deformed metal sheet, the rivet shank being still further compressed until the end of said rivet shank is flush with the outer surface of the sheet nearest the rivet end, the entire riveting operation being done in one, continuous, uninterrupted process.

5 15 2. A method of riveting a plurality of metal sheets as defined in claim 1 in which there are at least two metal sheets.

3. A method of riveting a plurality of metal sheets as defined in claim 1 in which there are at least three metal sheets.

4. A method of riveting a plurality of metal sheets as defined in claim 1 in which the walls of the rivet aperture are substantially perpendicular with the surfaces of the metal sheets being riveted.

25 5. A method of riveting a plurality of metal sheets as defined in claim 1 in which the metal surrounding the rivet aperture is deformed as part of the continuous, uninterrupted riveting operation.

6. A method of riveting a plurality of metal sheets as defined in claim 1 in which the rivets are flat head type rivets.

30 7. A method of riveting a plurality of metal sheets having different size apertures therein, which consists of inserting through said apertures a rivet having a head, a shank, and an end portion, one of said sheets being an outer sheet and adjacent to the said end portion, another of said sheets being next adjacent towards said head from said end portion, said latter sheet having a larger aperture than said outer sheet, holding said rivet head axially immobile and applying sufficient axial force against the end of the rivet shank to upset said rivet shank, compressing said shank so it expands and deforms the metal sheet nearest the rivet end, and displacing a portion of said sheet into the larger rivet aperture of the adjacent metal sheet, the rivet shank, being further compressed and shortened, and assuming a substantially bulbous shape and occupying the space created by the deformed metal sheet, the rivet shank being still further compressed until the end of said rivet shank is flush with the outer surface of the sheet nearest the rivet end, the entire riveting operation being done in one, continuous, uninterrupted process.
